UNITED STATES PATENT OFFICE

WALTER G. HENY AND ERNEST G. SCHUTZ, OF ELWOOD, NEBRASKA

TONGS

Application filed July 12, 1927. Serial No. 205,109.

This invention relates to tongs and is adapted particularly for use by blacksmiths for the purpose of holding the work in a positive manner while the same is being shaped or 5 formed in a desired manner.

The invention has for an important object the provision of means for adjusting the jaws of the tongs with respect to each other and securing the same in adjusted position.

Another object is to provide a tool of this character in which the parts entering into the construction thereof are reduced to a minimum, which is strong and durable, and 15 relatively inexpensive to manufacture.

Other objects and advantages reside in the special construction, combination and arrangement of the various elements forming the invention as more fully hereinafter described and claimed, reference being had to the accompanying drawing forming part hereof, wherein:

The drawing illustrates a perspective view of the invention illustrating the construction 25 thereof and showing the manner in which the jaws may be adjustably arranged.

Referring now to the drawing, we have illustrated our invention comprising a tool adapted for use as a pair of tongs and formed 30 of a pair of angular arms one end of each thereof constituting handles 5 with their opposite ends formed into jaws 6 and 7 respectively, said jaws being off-set longitudinally with respect to the handle portion, the off-set 35 portion 8 for the jaw 7 having a slotted opening 9 extending longitudinally therethrough and through which is inserted the off-set portion 10 of the other jaw 6. It will be observed that the jaw 6 is relatively narrower 40 than the jaw 7 whereby to permit the same to be readily inserted through the slot 9.

The jaw 7 is provided with a flattened gripping surface as indicated at 11 whereas the gripping edge of the jaw 6 is hook-shaped having its extreme end 12 flattened for engagement with the flattened gripping surface of the opposite jaw, the inner edge 13 of the hook-shaped portion of the jaw being adapted to embrace the side of a rounded 45 object, such as for instance, a chisel or

punch whereby to securely retain the same in position between said jaws.

The off-set section 10 of the jaw 6 is provided with a plurality of transversely extending openings 14 adapted to receive pins 15, 55 such as cotter pins or the like, with the ends of said pins engageable with the edges of the off-set portion 8 of the other jaw whereby to retain the jaws against relative longitudinal movement occurring thereon, namely in 60 one direction. By moving the pins 15 into the various openings the jaws may be secured in longitudinally adjusted position. In this manner the gripping area of the edge 13 of the jaw 6 may be increased to accommodate 65 various sized objects. If desired one of such pins may be inserted in the openings forwardly and rearwardly of the edges of the offset portion 8 to limit the extent of relative longitudinal movement in either direction.

When only one pin 15 is used, the same will serve to limit the relative longitudinal movement of the jaws in one direction in order to indicate the proper position of the jaws 75 for engaging work of a predetermined size, but at the same time, provides for the movement of the jaws in an opposite direction to enable the gripping of objects of either a larger or smaller size, depending upon the placing of the pin forwardly or rearwardly 80 of the offset 8, as the case may be, without necessitating a removal of the pin for the adjustment thereof.

It is obvious that the invention is susceptible to various changes and modifications 85 without departing from the spirit thereof or the scope of the appended claim and we accordingly claim all such forms of the device to which we are entitled.

We claim:

In a tool of the class described, a pair of jaws having handles formed at one end thereof, said jaws being offset longitudinally with respect to said handles, one of said jaws having its offset section provided with a longitudinally extending slotted opening adapted to receive the offset sections of said opposite jaw therein for the opening and closing movement of the jaws upon the operation of the handles and also providing a mounting for 95 100

the longitudinal movement of the jaws with respect to each other, said other offset sections having a plurality of transversely arranged openings, a pin removably carried in said openings adapted for engagement with one edge of said slotted offset section for retaining the jaws against longitudinal movement in one direction and permitting free longitudinal movement in an opposite direction, one of said jaws having a flattened gripping surface, and said other jaw having a hook shaped end providing a gripping surface at its inner edge and adapted to have its gripping area regulated by the longitudinal adjustment of said jaws.

10 In testimony whereof we affix our signatures.

WALTER G. HENY.
ERNEST G. SCHUTZ.
